(57) **CLAIM**

The ornamental design for a finger ring, as shown and described.

DESCRIPTION

1. Finger ring
- 1.1 : Perspective
- 1.2 : Front
- 1.3 : Back
- 1.4 : Right
- 1.5 : Left
- 1.6 : Top
- 1.7 : Bottom

The finger ring is shaped like a ring, which has a transverse width decreasing from its front part to its back part and which is interrupted by a transverse cut in the front part; one of the ends of said ring, defined by said cut, is shaped so as to resemble a horse's head seen in profile.
